UNITED STATES PATENT OFFICE.

ALTAMONT A. STALECKER, OF VENICE, ILLINOIS.

SHIPPING-CRATE.

No. 808,583.

Specification of Letters Patent.

Patented Dec. 26, 1905.

Application filed February 6, 1905. Serial No. 244,411.

To all whom it may concern:

Be it known that I, ALTAMONT A. STA-
LECKER, a citizen of the United States, resid-
ing at Venice, Madison county, State of Illi-
nois, have invented certain new and useful Im-
provements in Shipping-Crates, of which the
following is a specification containing a full,
clear, and exact description, reference being
had to the accompanying drawings, forming
a part hereof.

My invention relates to an improved ship-
ping-crate, and has for its object to provide
a compact and economical crate possessing
the advantages hereinafter described.

In the drawings, Figure 1 is a perspective
view of a crate embodying my invention.
Fig. 2 is an end view of the three sectional
sheets shown in Fig. 1 when the same are
nested for shipment as empties. Fig. 3 is a
transverse vertical mid-section of the sec-
tional crates when nested as shown in Fig. 2.

One object of my invention is to provide a
series of crates uniform in size and capacity
capable of being nested in groups of three,
both for purposes of shipment when filled
with goods and for return shipment as emp-
ties.

Referring to the drawings, I have shown a
series of three sectional crates, which are in-
dicated by the numerals 4, 5, and 6, respec-
tively, each of the said sectional crates being
rectangular and formed by nailing strips
upon the corner members 7, which are trian-
gular in section. Upon the upper edge of
each end of each of the said sectional crates I
have provided a pin 8 and a depression 9, cor-
responding in size with the exposed portion
of the pin 8, and upon the outer surface of
each of the said ends I have provided a hook
10. Upon the ends of each of the sections I
have provided the pins 11, with which the
hooks 10 are adapted to engage, so that the
sectional crates may be locked together, as
shown in Fig. 1.

As indicated in the drawings, the sectional

crates are intended to be of equal length,
width, and height, their width being greater
than their height and their length being less
than the combined height of two of the crates,
so that when the contents of the crate has 50
been removed any two of the said crates may
be attached together, as shown in Fig. 2, to in-
close and surround a third crate, thus effecting
great economy of space in the return of such
crates as empties. The total space occupied 55
by three empty crates arranged as shown in
Figs. 2 and 3 will therefore be one-third less
than the space occupied by the same number
of sectional crates when set up in position for
use with their contents, as shown in Fig. 1. 60

The function of the pins 8 and depression 9
is to hold the sectional crates against hori-
zontal slipping, and by means of staggering
the depressions 9 and pins 8 the pins will fit
into the depressions whether the crates are 65
set together top and bottom, as in Fig. 1, or
top to top, the upper sectional crate being in-
verted, as shown in Figs. 2 and 3.

Having thus described my invention, what
I claim as new, and desire to have secured to 70
me by the grant of Letters Patent, is—

An improved shipping-crate, comprising a
plurality of uniform-sized sections adapted
to be arranged one upon another, pins pro-
jecting upwardly from the top edges of the 75
top pair of end slats, there being correspond-
ing recesses formed in the lower edges of the
lower pair of end slats, and there being re-
cesses formed in the top edges of the top pair
of slats, which arrangement of pins and re-
cesses allows the sections to be reversed and 80
inverted when being superimposed to form a
complete crate; substantially as specified.

In testimony whereof I have signed my
name to this specification in presence of two 85
subscribing witnesses.

ALTAMONT A. STALECKER.
